(57) **CLAIM**

I claim the ornamental design for a split toe bunion sock, as shown.

DESCRIPTION

FIG. 1 is a left side view of the split toe bunion sock;
 FIG. 2 is a right side view of the split toe bunion sock;
 FIG. 3 is a front view of the split toe bunion sock;
 FIG. 4 is a bottom view of the split toe bunion sock; and,
 FIG. 5 is a rear view of the split toe bunion sock.
 The broken lines depict environmental subject matter that
 forms no part of the claimed design.
